UNITED STATES PATENT OFFICE.

DANIEL MILLS, OF PHILADELPHIA, PENNSYLVANIA, ASSIGNOR TO THE STANDARD SEWING MACHINE COMPANY, OF CLEVELAND, OHIO, A CORPORATION OF OHIO.

STOP MECHANISM FOR SEWING-MACHINES.

SPECIFICATION forming part of Letters Patent No. 728,269, dated May 19, 1903.

Application filed May 7, 1898. Serial No. 680,026. (No model.)

To all whom it may concern:

Be it known that I, DANIEL MILLS, a citizen of the United States, and a resident of Philadelphia, State of Pennsylvania, have 5 invented certain new and useful Improvements in Stop Mechanism for Sewing-Machines, of which the following description, taken in connection with the drawings here-with accompanying, is a specification.

o In certain classes of sewing-machines—such as buttonhole-stitching and button-sewing machines—it is desirable that the machines shall be automatically stopped after a certain predetermined number of stitches have been 15 taken, and it is also desirable that the machines should be thus stopped with the needle above the work and the take-up in a position at or adjacent to its upward limit of movement; and my present invention has 20 for its principal object to provide a stopping mechanism which will operate to automatically stop a machine at the time and in the position referred to without undue jar or shock to the same. This object I secure by 25 means of the construction and arrangement of parts, as hereinafter set forth in detail, and pointed out in the claims.

Referring to the accompanying drawings, Figure 1 is a side view of a sewing-machine 30 embodying my invention. Fig. 2 is a plan view of the sewing-machine bed-plate with the arm in section through line 2 2 of Fig. 1, showing part of a buttonhole-stitching mechanism and the connection between the same 35 and the stopping mechanism. Fig. 3 is a rear end view of the machine with the loose driving-pulley removed and its engaging lever and lever-supporting bracket in section through line 3 3 of Fig. 1. Fig. 4 is a vertical section of the machine through line 4 4 of Fig. 1 looking in the direction indicated by the arrow, and Fig. 5 is a central cross-section through the fast and loose pulleys with their connected parts upon the end of 45 the main driving-shaft.

To explain in detail, *a* represents a sewing-machine head, which may be of any ordinary construction, and *b* the fly-wheel or pulley, which is made fast upon the upper 50 driving-shaft *a'* of the machine in the usual

manner. This pulley *b* is provided with a hub *b'*, upon which is loosely mounted a driving-pulley *b*², which latter is supported to have a longitudinal movement upon the hub *b'*, whereby it may be moved at the will 55 of the operator by means as will hereinafter be described to and from a position to clutch with the pulley *b* and communicate motion to the machine. Any suitable form of clutch connection may be had between said pulleys, 60 the connection, as herein shown, being secured by means of a cone-faced hub *b*³ on the driving-pulley, which is adapted to enter an interiorly-cone-faced hub-sleeve *b*⁴ on the pulley *b* and when forced therein frictionally 65 hold the pulleys together.

As a means for moving or forcing the driving-pulley into engagement with the driven pulley *b* I have provided an elbow-lever *c*, which is pivotally supported at *c'* upon a 70 bracket *a*², secured upon the frame or arm of the machine and forming a part thereof. The lever *c* is arranged with one arm *c*² extending into a position to engage with the hub *b*³ of the driving-pulley and with its other arm *c*³ 75 extending beneath the pulley *b* and provided with a friction-brake *d* thereon for engaging with the latter. The arm *c*³ of the lever *c* is formed with an angle, so that a part thereof, as *c*⁴, upon which the brake is secured, will 80 extend parallel with the pulley *b*, as shown in Figs. 3 and 4.

The lever *c* connects with a slide-plate *e*, so as to be movable therewith by having a pin or projection *c*⁵ thereon extend into an opening *e'* in said plate. This slide-plate *e* is supported in a vertically-movable position upon the bracket *a*² by means of an embracing guide-plate *e*², secured to said bracket and is provided with a notch in one side thereof adjacent to its lower end into which one edge *e*³ of a horizontally-movable slide plate or latch *e*⁴ is adapted to extend when the machine is in operation, so as to hold the said vertical slide-plate *e* in a lowered position, with the lever *c* forcing the driving-pulley into operative engagement with the driven pulley and with the brake away from contact with the latter. 90

The plate or latch *e*⁴, which is supported on 100

- the bed-plate of the machine, is provided with a cut-away portion e^5 in one edge thereof, so that after it has been moved horizontally a certain predetermined distance by suitable 5 automatic mechanism, as will hereinafter be referred to, such cut-away portion will be brought opposite the notch in the slide-plate, so as to release the latter, and thereby allow the lever c to be moved to a position with one 10 arm releasing the driving-pulley from contact with the pulley b and the brake d on its other arm in engagement with the latter pulley, as shown by dotted lines in Fig. 1. Such movement of the lever c to stop the machine is secured by means of a spring f , which is secured upon the bracket a^2 , with one end exerting a normal upward pressure against the under side of the lower arm of the lever c , as shown. 15
- 20 Although the machine will be brought to a stop when the driving-pulley is thus released from engagement with the fast or driven pulley and the brake applied to the latter, it will not be stopped with the parts in any definite 25 or predetermined position, as is desirable, and in order to accomplish this I have provided a means as follows: A collar or ring h is loosely supported upon the hub of the pulley b and is provided with a fixed pin h' thereon, which 30 projects through an elongated slot h^2 in said pulley. On that side of the pulley opposite the ring h a coiled spring i is supported, with one end acting against a fixed pin h^3 on the pulley b and its opposite end acting against 35 the said pin h' of the ring h , so as to movably hold the said ring and pulley in a normal stationary position relative to each other, with the pin h' of the ring at one end of the slot h^2 in the pulley, as shown in Fig. 3. 40
- 45 A fixed arm k of the lever c extends into a position opposite one side of the ring h and is provided with a bent end, as at k' , forming a catch which is adapted to be automatically moved into a position to engage with a projection h^4 on the said ring h , as shown by dotted lines in Fig. 1, when the lever c is operated to release the driving-pulley from the pulley b and move the brake d into engagement with the latter, as hereinbefore described. 50 When the arm k thus engages with the projection on the ring h , the latter is brought to a positive stop, while the pulley b under the momentum of the machine may continue its rotation, as shown by dotted 55 lines in Fig. 3. Such further rotation of the pulley, however, is against the pressure of the spring, whose opposite end has been made stationary with the ring h , and after its momentum has been overcome the reaction of 60 the spring is sufficient to return the pulley to a position with the end wall of its slot h^2 against the now-stationary pin of the ring h , in which position of the pulley the machine is in a definite desired position, with the needle above the work and the take-up at or adjacent to its upward limit of movement, as 65 shown in Fig. 1. In this manner the machine

may be brought to a stop with its parts in a desired position without undue jar or shock to the same. The brake d , carried by the lever c and operating as described, serves to lessen the strain upon the spring i in braking the pulley b ; but it will be obvious that such brake may be dispensed with, if so desired, as the stopping mechanism is complete without the same. 70

When the lever c is moved to force the pulley b^2 into engagement with the pulley b for the purpose of again starting the machine, such movement throws the catch end of the 80 arm k out of engagement with the projection on the ring h and in a position at one side the path of movement of the same, as shown in Fig. 1, so as to release said ring and allow it to rotate with the pulley b . 85

The horizontally-acting slide-latch e^4 , which is operated to release the slide d at a certain predetermined time for the purpose of causing the machine to be stopped, may be operated by any suitable automatic mechanism, 90 the same as herein shown being the button-hole-stitching mechanism illustrated and described in another application of mine now pending, filed November 9, 1896, and bearing Serial No. 611,486, which in part is as follows: 95 A slide-plate m , which connects with the work-clamp in my said buttonhole-stitching machine to give the same its longitudinal movement, is supported on the bed-plate of the machine and provided with two pins $m'm'$, between which a rotating heart-cam m^2 operates to communicate a longitudinal forward and 100 backward movement thereto. A lever n , centrally pivoted on the bed-plate of the machine, is connected at one end with the plate m to be moved thereby and at its opposite end is provided with an adjusting-screw n' , which bears against one end of the slide-latch e^4 . By this means as the plate m is moved forward during the stitching of one side of a 105 buttonhole the lever n is moved thereby in a direction away from engagement with the slide e^4 , and as said plate m is moved backward or in the opposite direction during the stitching of the other side of the buttonhole 110 the lever n is moved into engagement with the said plate e^4 and moves the latter longitudinally, so that when the plate m has been moved the proper distance to complete the 115 buttonhole the latch e^4 will also have been moved the necessary distance to bring the notch or cut-away portion e^5 therein opposite the vertical slide e to release the latter, and thereby allow the stopping mechanism to operate to stop the machine in the manner as 120 described. By turning the adjusting-screw n' in the proper direction, so that its end will project more or less beyond the lever n , the timing of the movement of the slide e^4 may be regulated to release the slide d sooner or 125 later, according to the number of stitches it may be desired to have the machine make before being stopped. The machine may also be stopped at any time independent of the 130

automatic mechanism by operating the latch e^4 by hand, the forward end of which is turned up to enable the same to be grasped by the operator for such purpose.

5 A chain or other suitable connection extending beneath the machine may be attached to the slide e as a means for lowering the same when it is desired to start the machine, and a spring o , acting against the horizontal latch e^4 to move the same longitudinally, causes its edge to enter the notch in the slide d when lowered to a position opposite the same.

If for any reason the operator desires to have the machine continue running without being 15 automatically stopped after a certain predetermined number of stitches have been taken, this may be done by moving a swinging catch p , which is pivotally supported upon the bracket a^2 , into engagement with a pin p' on the lever c , so as to hold the latter in its position, with the pulley b^2 in contact with the pulley b and the braking mechanism in inoperative position. When the lever c is thus held, there is no movement of the same when 25 the latch e^4 is moved into position to release the slide e .

Having thus set forth my invention, what I claim as new, and desire to secure by Letters Patent of the United States, is—

30 1. In a sewing-machine, the combination, with the main shaft, of a pulley made fast on said shaft and provided with an elongated slot therein, a ring loosely supported on said shaft and provided with a pin extending through the said slot in the pulley, a spring 35 yieldingly holding said ring with its pin in a normal position against an end wall of said slot, a pivoted rocking lever having means for engaging with said ring to stop rotation 40 of the same and the connected pulley, and means, embodying a vertical slide and a horizontally-acting latch, for automatically controlling the action of said lever, for the purpose set forth.

45 2. In a sewing-machine, the combination, with the main shaft having fast and loose pulleys, the former having a yieldingly-con-

nected stop projection at one side thereof, of a pivoted rocking lever having one arm for engaging with the loose pulley to force the same into contact with the fast pulley, and a second arm for engaging with the stop projection of the fast pulley, the said arms being so arranged that when the lever is operated to place one arm into operative position, 55 the other arm is thereby moved or placed in an inoperative position, and means, embodying a slide, for automatically controlling the action of said lever, for the purpose set forth.

3. In a sewing-machine, the combination 60 with the main shaft having fast and loose pulleys, the former having a connected stop projection at one side thereof, of a pivoted lever having one arm for engaging with the loose pulley to force the same into contact 65 with the fast pulley, and a second arm for engaging with the stop projection of the fast pulley, a spring for movably holding said lever in a normal position with one arm releasing the loose pulley and its other arm in engagement with the stop projection of the fast pulley, and a catch device for holding the lever in a position against the pressure of the 70 spring with one arm holding the loose pulley in operative contact with the fast pulley and 75 its other arm releasing the connected stop projection of the latter, for the purpose set forth.

4. In a sewing-machine, the combination, 80 with the main shaft having fast and loose pulleys, the former being provided with a stop projection, of a lever having one arm for engaging with the loose pulley to force the same into operative engagement with the fast pulley, a second arm for engaging with the stop 85 projection of the fast pulley, and a third arm carrying a brake for engaging with the latter, and means for controlling the action of said lever, for the purpose set forth.

DANL. MILLS.
